George H. Westbrook, of New York, N.Y.
Letters Patent No. 1950-Dated June 7, 1864.

Design for a Trade Mark

The schedule referred to in these Letters Patent and making part of the same.

To all whom it may concern:

Be it known that I, George H. Westbrook, of the City, County, and State of New York, have invented or produced a new and original design on paper as a Trade Mark; and I do hereby declare that the following is a full and exact description of the same.

The design represents a female figure of Hygeia, or the Goddess of Health seated upon a barrel, behind which is seen one end of another barrel standing. At her right side is an urn or dish standing upon a pedestal, in front of which is represented a small piece of chemical apparatus. Around the left arm is a serpent entwined, with its head over the urn, or dish, in the act of drinking or lapping from it. The right arm is elevated from the elbow, the hand grasping the neck of a bottle.

Within the circle which surrounds the figure are the words
"G. H. Westbrook's Hygienic Cider." A Copy of the design is hereto annexed.

What I claim as my invention, and desire to secure by Letters Patent is - The design in its position, arrangement and surroundings, including the letters and words as a part of said design.
